(57) **CLAIM**

The ornamental design for an insect attractive light fixture, as shown and described.

DESCRIPTION

FIG. 1 is a perspective view of an insect attractive light fixture of a first embodiment;

FIG. 2 is a front elevation of the insect attractive light fixture of the first embodiment;

FIG. 3 is a right side elevation of the insect attractive light fixture of the first embodiment, the left side elevation being a mirror image thereof;

FIG. 4 is a top plan of the insect attractive light fixture of the first embodiment, the bottom plan being a mirror image thereof;

FIG. 5 is a rear elevation of the insect attractive light fixture of the first embodiment;

FIG. 6 is a cross section of the insect attractive light fixture taken in the plane of line 6—6 of FIG. 1;

FIG. 7 is a perspective view of an insect attractive light fixture of a second embodiment;

FIG. 8 is a front elevation of the insect attractive light fixture of the second embodiment;

FIG. 9 is a right side elevation of the insect attractive light fixture of the second embodiment, the left side elevation being a mirror image thereof;

FIG. 10 is a top plan of the insect attractive light fixture of the second embodiment, the bottom plan being a mirror image thereof;

FIG. 11 is a rear elevation of the insect attractive light fixture of the second embodiment; and,

FIG. 12 is a cross section of the insect attractive light fixture taken in the plane of line 12—12 of FIG. 7.

The broken lines shown in the drawings indicate structure and features which form no part of the claimed design.
